SMOKER'S ACCESSORY

Millard F. Comstock, Fort Erie, Ontario, Canada

Application October 30, 1953, Serial No. 389,435

4 Claims. (Cl. 131—242)

The invention relates generally to smokers' accessories and more particularly to an improved cigarette tray and butt disposal unit.

A primary object of the invention is to provide a cigarette butt disposal unit which is equipped with a cigarette holder rack having butt clearing means operable incidental to closing of a cover of the unit.

Another object of the invention is to provide an improved cigarette butt disposal unit of the aforesaid type which is relatively simple and inexpensive to make by mass production methods.

Other objects and advantages of the invention will appear from the specification hereinafter.

In the drawing:

Fig. 1 is a perspective view showing an embodiment of the invention;

Fig. 2 is an enlarged end elevational view, partly in section, of the device of Fig. 1; and

Fig. 3 is a fragmentary view showing a detail of Fig. 2.

Referring now to the drawing there is shown a container 10 of generally rectangular open top form comprising opposite end portions 12, opposite side portions 14 and a bottom portion 16 as shown in Fig. 2. The container 10 may be formed from any suitable material such as for example, of a suitable heat-resistant plastic by an injection molding process, or the like.

As shown in Figs. 1 and 2, the container 10 is fitted with a duo-section cover 18 comprising hinged sections 20 and 22 having laterally extending marginal edge portions adapted to snugly embrace the upper and outer sides of the container when mounted in a closed position thereon. The section 20 is preferably arranged to be relatively wider than the section 22 whereby these sections will be hinged along a line substantially offset from the longitudinal axis of the container 10 as indicated at 24. Thus, the outer edge portion of the cover section 20 will overlap and protrude beyond the outer edge of the cover section 22 to provide a finger catch portion as when the cover section 20 rests in its "open" position, as shown in Figs. 1 and 2, for convenience in flipping the lid into closed position. The hinge 24 may be formed as is well known by aligning a plurality of radially bent end portions 26 of the inner sides of the cover in intermeshed contiguous relation and then fitting a stiff wire to extend therethrough having its end portions enlarged to maintain the hinged relation.

A particular feature of the invention is to provide a cigarette holder rack 28 in fixed relation with the inner edge portion of the inside face of the cover section 20. The rack 28 is formed with a right-angular cross-section having a flange 30 fixed as aforesaid to the cover and a flange 32 extending laterally away therefrom and being provided with a series of spaced cigarette receiving slots 34. The slots 34 may be cut into the edge of the member 28 so that the side walls thereof will be uniformly spaced to have press-fitted therebetween a cigarette 36 as shown in Figs. 1 and 2. Thus, it will be appreciated

2

that the rack 28 may be used to hold a cigarette temporarily deposited in one of its slots 34 without danger of having it accidentally roll on a table or floor as is the case with some ash trays. Furthermore, if the unit is left unattended a lit cigarette mounted therein will burn itself back to the rack 28 and go out or fall into the inside cover area of the cover section 20 from whence it will not roll out, whereas the ashes formed during burning of the cigarette portion forwardly of the rack 28 simply will fall into the container 10.

As shown in Figs. 1, 2 and 3, a cigarette butt clearing device 38 is fixed to the inside edge portion of the inside face of the cover section 22 as by means of a flange portion 40 thereof. The device 38 is formed to have a portion 42 bent laterally of the flange 40 so as to be substantially in the plane of the flange 32 and then is bent laterally of the portion 42 into a rack-clearing comb portion 44 extending beyond the cover portion 22 and providing a plurality of spaced teeth or lugs 46 to extend therefrom and being arranged to intermesh between the side wall portions of the slots 34 incidental to pivoting of the cover section 20 into its closed position. Thus, as shown in Figs. 2 and 3, any cigarette butts 36 carried by the rack 28 will be automatically cleared therefrom incidental to closing of the cover section 20 by virtue of the butts being pressed out of the slots 34 by the lugs 46 so as to fall into the container 10 in the manner shown in Fig. 3.

It will be appreciated, of course, that the device of the invention will serve as a large capacity improved ash tray in that lit cigarettes will not accidentally roll out of the unit to cause a fire hazard and a messy ash dispersal condition in the vicinity thereof. In addition, short cigarette butts may be cleared from the rack by simply closing the hinged cover section 20 to cleanly deposit the cigarette remains in the container 10 without possibility of injury to the smoker. And furthermore, the hereinabove described hinged cover portions 20 and 22 are arranged to be easily detached by simply lifting them off as a unit from the container 10 as for example to provide easy access to the parts of the unit for cleaning purposes.

Therefore, it will be understood that although only one particular form of the invention has been shown and described in detail it will be apparent to those skilled in the art that the invention is not so limited but that various changes may be made therein without departing from the spirit of the invention or the scope of the appended claims.

I claim:

1. A cigarette butt and ash receiver unit comprising a generally open top container, a cover device comprising a pair of hinged interconnected cover portions adapted to be mounted upon the top of said container, a cigarette holder rack including spaced lugs protruding from the inside face of one of said cover portions, and a rack clearing device extending from the inside face of the other of said cover portions; said rack clearing device having a plurality of spaced lugs adapted to intermesh with the lugs of said rack when said cover portions are disposed in container-closing position.

2. In a cigarette smoker's accessory, an ash receiver having relatively hinged removable cover portions, rack members fixed to the bottom faces of said cover portions at opposite sides of the hinge connection therebetween, said rack members each having a plurality of lug portions protruding therefrom in spaced relation and being arranged to intermesh when said cover portions are swung into receiver-closing position on said receiver.

3. A cigarette butt and ash receptacle comprising a generally open top container, duo-section cover portions having laterally downwardly extending marginal rim

portions adapted to snugly embrace the upper edge portions of said container when in closed position, said cover portions being hinged at their abutting edges, a cigarette holder rack attached to the inner face of one of said cover portions and being substantially coextensive with and spaced slightly inwardly from the inside edge thereof, and a rack clearing means depending from the lower face of the other of said cover portions and being substantially coextensive with and spaced slightly inwardly from the inside edge thereof; said racks having a plurality of spaced lugs adapted to intermesh with each other when said cover portions are in closed position.

4. In a cigarette smoking box, a cover having relatively hinged removable cover portions having depending marginal edges adapted to overhang the edges of

5

10

15

the box opening, rack members fixed to the undersides of the cover portions along opposite sides of the hinge connection therebetween and each having a plurality of lug portions protruding therefrom in spaced relation substantially coextensive with said hinge connection, said lug portions of said rack members being arranged to intermesh incidental to closing of said cover when in mounted position on said box.
